DESIGN FOR A TIRE CASING

Charles W. Yelm and Harry M. Flint, Denver,
Colo., assignors to The Gates Rubber Company,
Denver, Colo.

Application October 14, 1935, Serial No. 58,981

Term of patent 7 years

To all whom it may concern:

Be it known that we, Charles W. Yelm and Harry M. Flint, citizens of the United States, residing at Denver, in the county of Denver and State of Colorado, have invented a new, original, and ornamental Design for a Tire Casing, of which the following is a specification, reference being had to the accompanying drawing, forming a part thereof in which

Figure 1 is a perspective view of a tire casing, a section only being illustrated in full lines, showing our new design; and

Figure 2 is a sectional view taken on line 2—2,
Figure 1.

We claim:

The ornamental design for a tire casing, as shown and described.

In testimony whereof we hereunto affix our signatures.

CHARLES W. YELM.
HARRY M. FLINT.
